ELECTRIC CIRCUIT CONNECTER

Filed Dec. 30, 1927

Inventor:
George Carlson,

by Alexander S. Knott,
His Attorney.

UNITED STATES PATENT OFFICE

GEORGE CARLSON, OF ANSONIA, CONNECTICUT, ASSIGNOR TO GENERAL ELECTRIC COMPANY, A CORPORATION OF NEW YORK

ELECTRIC-CIRCUIT CONNECTER

Application filed December 30, 1927. Serial No. 243,705.

My invention relates to electric circuit connectors. More particularly it relates to connectors of the type especially adapted for use in connecting the so-called tap or ground wire of electrical apparatus to ground as, for example, through means of a pipe line, a rod, or the like, as is customary in connection with telephone apparatus or lightning arresters.

Devices of the above general character are well known but are complicated or ineffective, not substantial in structure, unreliable in maintaining a permanent ground connection, not effectively adjustable for use in connection with pipes, rods and the like of different sizes and expensive.

Among the objects of my invention are to provide a connector which avoids the above objections. However, the invention will be more readily understood from the accompanying specification and claims, reference being had to the accompanying drawing, Fig. 1 of which shows in perspective a ground connector comprising the features of the invention, and Fig. 2 of which shows the device of Fig. 1 in section. Fig. 3 is a modified form of the device.

Referring to the drawing more in detail, it will be seen that the connector is shown connecting two conductors 2 and 3. In this connection it may be assumed that the conductor 3 is a grounded line such as a water pipe. The clamp comprises a pair of jaws 4 and 5, duplicates of each other. The jaw 4 is provided on one side with a heel element 6. Similarly, the jaw 5 is provided on the opposite side as may be readily seen by referring to Fig. 2, with a corresponding heel 7. The jaw 5 is provided with a notch 8 for receiving the heel 6, while the jaw 4 is provided with a notch 9 for receiving the heel 7. It will be seen that the lower ends 10 and 11 of the jaws are threaded for receiving the nut 12 which latter is tapered, the larger opening being on the upper side, Fig. 2. The object of the heels 6 and 7 and of the notches 8 and 9 is to properly line up the jaws 4 and 5 with respect to each other so that the threads will properly line up. It will be seen, therefore, that by means of the nut 12 the jaws 4 and 5 may be tightly clamped about the conductor 2 as shown,

thereby insuring a tight and effective connection between the jaws and the conductor. Such a connection can be easily, effectively and quickly set up. Furthermore, this type of construction makes it unnecessary to have the end of the conductor 2 threaded. The jaws 4 and 5, furthermore, are perforated in the upper section for receiving a bolt 13 as shown. The clamp also comprises a metal strap element 14 which is provided with a series of perforations 15 along its length or which, if necessary, may be easily perforated at some other point or points. These perforations are preferably spaced apart, not at equal intervals, but at unequal intervals as indicated.

With this arrangement it is possible to run the strap around the pipe 3 with two of the perforations 15 in juxtaposition between the jaws 4 and 5 as shown in Fig. 2. When the strap is thus brought into position about the pipe 3 and threaded by the bolt 13 the strap 14 may be tightly drawn about the pipe into effective electrical connection with the pipe and with the jaws by tightening the nut 16 of the bolt 13, thereby drawing the jaws together, thus effectively, simply, and substantially grounding the conductor 2 with the pipe 3. It is obvious that with a connector of the foregoing character connection may thus be made between the conductor and the pipe regardless of the size of the pipe, inasmuch as the size of the loop formed by the strap 14 about the pipe and between the jaws may be varied in length by bringing different perforations 15 into juxtaposition.

It is obvious that a connector device of the foregoing character can be easily and cheaply manufactured, and quickly, easily and effectively put together anywhere and at any time under almost any conditions with a minimum amount of effort and consumption of time. It will be understood that in forming the loop about the pipe 3 it may be convenient, after the proper perforations are brought into juxtaposition for receiving the bolt 13, to cut off the ends of the strap below the bolt 13.

In the modified form of the device shown in Fig. 3, it will be seen that the jaws are formed so that they may be brought actually

against the conductor 2. The face of the jaw is cut away so as to permit the strap that binds the conductor 2 to pass into the jaws without interfering with the direct contact of the jaws and the conductor 2.

5 With the type of device shown in the drawing, it is evident that both of the jaws are identical, which of course simplifies the manufacture. These jaws are so constructed that 10 any two of them may be brought together and assembled to form the connector of the invention. While in Fig. 1 I have shown an ordinary form of nut 16, a wing nut may be substituted for this type of nut.

15 In the event that the conductor 2 constitutes a conduit for a cable or conductor, the conductor itself may be directly secured and soldered, if necessary, directly to the strap that binds the ground conductor 3 as indicated in 20 dotted lines in Fig. 2.

25 It will be understood that while I have elected to disclose my invention in connection with a specific form of construction, I do not wish to be limited to such construction inasmuch as in view of the disclosure, variations may be made without departing from the spirit of the invention or the scope of the 30 claims appended hereto.

What I claim as new and desire to secure 35 by Letters Patent of the United States, is:

1. An electric connector having in combination a pair of jaws, means for clamping the ends of said jaws to an electric conductor, and a strap of conducting material projecting 40 in the form of a loop from between the jaws at the other end of the connector whereby an electric conductor may be inserted through said loop and means for clamping the loop about the conductor whereby an electric connection may be established between the two 45 electric conductors through said connector.

2. An electric connector having in combination a pair of jaws, means for clamping the ends of said jaws to an electric conductor, a 50 strap of conducting material projecting in the form of a loop from between the jaws at the other end of the connector whereby an electric conductor may be inserted through said loop and means for clamping the loop about the conductor whereby an electric connection may be established between the two 55 electric conductors through the medium of said connector, and means for anchoring the ends of the loop between said jaws.

3. An electric connector having in combination a pair of jaws, means for clamping the ends of said jaws that form one end of the connector to an electric conductor, a strap of conducting material projecting in the form of 60 a loop from between the jaws at the other end of the connector whereby an electric conductor may be inserted through said loop and an electric connection established between the two conductors through the medium of said connector, and means for drawing the other 65

ends of said jaws together to tighten said loop about the conductor inserted therethrough.

4. An electric connector having in combination a pair of jaws, means for clamping the 70 ends of said jaws that form one end of the connector to an electric conductor, a strap of conducting material projecting in the form of a loop from between the jaws at the other end of the connector whereby an electric conductor may be inserted through said loop to establish an electric connection between the two conductors through the medium of said connector, and means for drawing the other ends of said jaws together to tighten said loop about the conductor inserted therethrough, said last means comprising a bolt threading both of said jaws. 75

5. An electric connector having in combination a pair of jaws, means for clamping the 80 ends of said jaws that form one end of the connector to an electric conductor, a strap of conducting material projecting in the form of a loop from between the jaws at the other end of the connector whereby an electric conductor may be inserted through said loop to establish an electric connection between the two conductors through the medium of said connector, means for anchoring the ends of the 85 loop between said jaws, and means for drawing the other ends of said jaws together to tighten said loop about the conductor inserted therethrough, the said means for anchoring said loop and the means for clamping the jaws to tighten the loop consisting of a bolt 90 threading both the jaws and the strap. 95

6. An electric connector having in combination a pair of jaws, means for clamping the 100 ends of said jaws that form one end of the connector to an electric conductor, a strap of conducting material projecting in the form of a loop from between the jaws at the other end of the connector whereby an electric conductor may be inserted through said loop to establish an electric connection between the two 105 conductors through the medium of said connector, means for anchoring the ends of the loop between said jaws, means for drawing the other ends of said jaws together to tighten said loop about the conductor inserted therethrough, and means on the ends of said jaws 110 for seating the said second conductor when the loop is tightened. 115

In witness whereof, I have hereunto set my hand this 27th day of December, 1927.

GEORGE CARLSON.
